(57) CLAIM

The ornamental design for a bailing bucket, as shown and described.

DESCRIPTION

FIG. 1 is a front elevation view of the bailing bucket in accordance with my invention;

FIG. 2 is a back elevation view of FIG. 1;

FIG. 3 is a first side elevation view of FIG. 1; the second side elevational view being a mirror image thereof;

FIG. 4 is a top plan view of FIG. 1;

FIG. 5 is a bottom plan view of FIG. 1;

FIG. 6 is a perspective view of the bailing bucket of FIG. 1; and,

FIG. 7 is a cross-sectional view taken along line 7—7 in FIG. 6.

The broken lines in the Figures are for illustrative purposes only and form no part of the claimed design.
